US00D860146S

(12) **United States Design Patent** (10) Patent No.: **US D860,146 S**
(45) Date of Patent: ** *Sep. 17, 2019

(54) **WAFER CARRIER WITH A 33-POCKET CONFIGURATION**

(71) Applicant: **Veeco Instruments Inc.**, Plainview, NY (US)

(72) Inventors: **Yuliy Rashkovsky**, Millburn, NJ (US); **Mandar Deshpande**, Bridgewater, NJ (US); **Alexander Gurary**, Bridgewater, NJ (US); **Sandeep Krishnan**, Jersey City, NJ (US); **Aniruddh Parekh**, New York, NY (US)

(73) Assignee: **Veeco Instruments Inc.**, Plainview, NY (US)

(*) Notice: This patent is subject to a terminal disclaimer.

CLAIM

The ornamental design for a wafer carrier with a 33-pocket configuration, as shown and described.

DESCRIPTION

FIG. 1 is a perspective view of a wafer carrier with a 33-pocket configuration, showing our new design.

FIG. 2 is a top plan view thereof.

FIG. 3 is a bottom plan view thereof.

FIG. 4 is a right side view thereof, with the left side view, front view, and rear view being identical; and,

FIG. 5 is an enlarged portion view taken from encircled portion labeled FIG. 5 in FIG. 1.

In each of the figures, portions or features shown in even broken lines form no part of the claimed design. The dashed-dot lines depict the boundary of the enlarged portion view of FIG. 5, and form no part of the claimed design
